UNITED STATES PATENT OFFICE.

SVEND A. HANSEN, OF GLENWOOD, CALIFORNIA.

COIN-ACTUATED TIME-CONTROLLED MECHANISM FOR CONTROLLING THE USE OF TELESCOPES AND LIKE INSTRUMENTS.

Application filed August 3, 1925. Serial No. 47,958.

To all whom it may concern:

Be it known that I, SVEND A. HANSEN, a citizen of the United States, residing at Inspiration Point, Glenwood, in the county of 5 Santa Cruz and State of California, have invented certain new and useful Improvements in Coin-Actuated Time-Controlled Mechanism for Controlling the Use of Telescopes and like Instruments, of which the 10 following is a specification.

This invention relates to an apparatus for use in connection with optical instruments, such as telescopes and binoculars, whereby the time of use of the instruments 15 may be readily controlled and its use only permitted on the depositing of an operating coin or token.

The invention has for its principal objects to provide, preferably within the tubular portion of the binocular or telescope, of light controlling means, manually opened, on the depositing of a controlling coin or token and with which is associated time controlled mechanism for admitting of the automatic closure of the light controlling 25 mechanism after the expiration of a predetermined period. A further object is to provide a plunger actuated mechanism in which the depositing of the controlling coin or token serves as an operating abutment for the plunger during its movement to open the light controlling mechanism.

With the above mentioned and other objects in view, the invention consists in the 30 novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages 40 of the invention.

45 In the drawings:—

Fig. 1 is a transverse sectional view through the tubular barrel of a telescope, illustrating the preferred embodiment of my invention in use therewith.

50 Fig. 2 is a transverse sectional view through the housing containing the light controlling operating mechanism.

Fig. 3 is a sectional view on the broken line 3—3 of Fig. 1.

55 In the drawings, wherein like characters

of reference designates corresponding parts, 1 indicates the tube of a telescope, the optical members of which are not illustrated, and within said tube is positioned a circular support 2 (Fig. 3) which carries shutter 60 members 3 hinged thereto as at 4. At the base of the shutter members is rotatably mounted a pinion shaft 5 extending through the tube 1, the shaft carrying at its upper end a cross head 6 within the ends of which 65 are pivotally connected links 7, the latter being in turn pivotally connected to the respective levers 8, one associated with each hinge 4 of the respective shutters 3. At its lower end the shaft 5 carries a laterally disposed arm 9 with which is connected an operating rod 10 mounted to reciprocate within a bore 11 in a protecting housing 12, attached in any suitable manner to the tube 1.

70 It will be observed that an endwise movement of the operating rod will cause a simultaneous opening and closing movement of the shutters 3, dependent on the direction of movement of the rod 10.

Coiled about the shaft 5 and secured at 80 one end, as at 13, to the part 2, and at its opposite end to the arm 9, is a spring 14, the action of which is to normally maintain the shutters 3 in closed position, as in the drawings.

To the end of the protecting housing 12 is secured a box or shell 15 into which extends the rod 10, the same sliding in a guide member 16 depending from the underside of the top wall of the box.

Carried by one side wall of the box 15 is a lever bracket 17 in the end of which is pivotally mounted on a fulcrum pin 18 a bifurcated plate 19, the upper surface of which carries a substantially U-shaped flange 20, 95 open at its upper end as at 21, to register with a coin or token reception opening 22 in the outer side wall of the box 15, Fig. 1.

100 Mounted to reciprocate in a tubular guide 23 in the top wall of the box is a plunger 24, the lower end of which is in alignment with the space 25 between the frucations of the plate 19 and the normal depression of the plunger will admit of its lower end passing through the space 25.

105 A spring 26 normally maintains the plunger 24 elevated, and said plunger carries a plate restoring hook 27 extending beneath the edge of the plate 19.

110 At one end the pinion 18 carries a lever

28 to which is connected a coiled spring 29, designed to maintain the plate either in full or dotted line position, as in Fig. 1, dependent on whether the plunger 24 is in elevated or depressed position when a coin is present in lever 19.

At its opposite end the pinion 18 carries an operating rod setting finger 30 adapted on the depression of the plate 19 to engage 10 with a pin 31 on the rod 10 and cause an outward movement of the rod, which will cause an opening of the shutters 3.

A rod retaining pawl 32 pivoted to the member 16 is adapted on the rearward movement of rod 10 to receive in its notch 33 15 a pin 34 carried by the rod 10, and the action of a spring 35 in forcing said pawl upwardly, causes an interlocking of the pin 34 with in the notch 33 and retains said shutters in 20 open position.

Within the box 15 is positioned, any well known type of time controlled mechanism, conventionally illustrated as at 36, one element of the same being a governor controlled ratchet wheel 37 with which cooperates a pawl 38 on the time controlled lever 39, the latter having arms 40 and 41 extending at right angles from each other at its ends, and the latter arm carrying a weighted portion 42. Laterally from an arm 43 associated with the member 18 is a pin 44 operating in a slot 45 in the arm 40, and depending from the pawl 32 is a trip member 46 extending through an aperture 47 in the arm 41, the trip member carrying a head 47 at its lower end.

On the insertion of a coin or token within the opening 22, the same closes the opening 25 in plate 19. A downward depression of 25 plunger 24 causes its lower end to rest on the coin or token and a depression of the 40 plate 19 is accomplished. During this movement, the arm 43 and pin 44 are raised, causing a raising of the lever 39 and a consequent elevation of pawl 38 in the teeth of the ratchet 37. This downward movement of the plate also causes an outward reciprocation of the rod 10 and the interlocking of the pin 34 in the recess or notch 33 opening 45 the shutters 3.

On the release of pressure from plunger 24, the spring 26 elevates the plunger and in doing so the hook 27 elevates the plate 19 from which the coin or token has slipped 55 and deposited in the box. This movement releases the holding pressure of pin 44 in the upper end of slot 45 and admits of the operation of the time controlled mechanism 36, the lever 39 of which on arriving at its lowest 60 position causes contact between the

underside of arm 41 and head 47, withdrawing pawl 32 from engagement with pin 34 and admitting of spring 14 to close the shutters 3.

It will be understood that the operation of 65 the time controlled mechanism when one set may be varied by adjusting the head 47 on member 46.

I claim:—

1. In combination with an optical instrument for use in view distant objects and including a tube, a shutter mechanism therein for controlling light passing therethrough, an operating plunger, a plunger actuated lever, an element associated with the shutter mechanism and acted on by the lever to cause an opening of the shutter mechanism, a pawl for holding the shutter mechanism open, time controlled means for releasing the pawl, and means for closing the shutter mechanism on the release of the pawl, said plunger and plunger actuated lever rendered cooperative on the positioning of a token between the same.

2. In combination with an optical instrument for use in viewing distant objects and including a tube, shutter mechanism within the tube for controlling light passing therethrough, shutter operating means extending exteriorly of the tube, a plunger, a plunger actuated lever, an operative connection between the plunger actuated lever and shutter operating means, means for retaining said shutter operating means in shutter opening position, and time controlled means for releasing said shutter operating means, said plunger and plunger actuated lever rendered cooperative on the positioning of a token between the same.

3. In combination with an optical instrument for use in viewing distant objects and including a tube, a shutter mechanism therein for controlling light passing therethrough, an operating plunger, a plunger actuated lever, an element associated with the shutter mechanism and acted on by the lever to cause an opening of the shutter mechanism, a pawl for holding the shutter mechanism open, time controlled means movable into set position on the opening of the shutter mechanism, for releasing the pawl, and means for closing the shutter mechanism on the release of the pawl, said plunger and plunger actuated lever rendered cooperative on the positioning of a token between the same.

In testimony whereof I have signed my name to this specification.

SVEND A. HANSEN.
